United States Patent Office.

JAMES L. HAVEN, OF CINCINNATI, OHIO.

Design No. 4,924, dated May 23, 1871.

DESIGN FOR A HOUSING-PLATE.

The Schedule referred to in these Letters Patent and making part of the same.

I, JAMES L. HAVEN, of Cincinnati, in the county of Hamilton and State of Ohio, have invented and produced a new and original Design for a Housing-Plate, of which the following is a specification.

The nature of my design is fully represented in the accompanying illustrations, to which reference is made.

Claim.

I claim as my invention—

The design for a housing-plate, as shown. In testimony of which invention I hereunto set my hand.

JAMES L. HAVEN.
